[57] CLAIM

The ornamental design for a hair care center, as shown and described.

DESCRIPTION

FIG. 1 is a front and left side perspective view of a hair care center showing a first version of my new design having hinged mirrored doors, both being in the closed position; FIG. 2 is a front elevational view thereof; FIG. 3 is a rear elevational view thereof; FIG. 4 is a left side elevational view thereof; FIG. 5 is a right side elevational view thereof; FIG. 6 is a top plan view thereof; FIG. 7 is a bottom plan view thereof; and, FIG. 8 is a front elevational view showing a second version of my new design having sliding mirrored doors, one door being in the open position.
